UNITED STATES PATENT OFFICE.

ALFRED NOBEL, OF PARIS, FRANCE.

MECHANISM FOR FORGING HOLLOW SHAFTS, GUNS, OR OTHER SIMILAR METALLIC ARTICLES.

SPECIFICATION forming part of Letters Patent No. 599,472, dated February 22, 1898.

Application filed July 25, 1895. Serial No. 557,156. (No model.) Patented in Sweden January 26, 1895, No. 6,827; in Germany June 10, 1895, No. 84,788; in England June 10, 1895, No. 11,346; in France June 10, 1895, No. 248,057; in Austria June 11, 1895, No. 45/2,522; in Hungary June 20, 1895, No. 3,057; in Belgium July 29, 1895, No. 116,745, and in Italy September 30, 1895, XXX, 39,463, LXXVII, 252.

To all whom it may concern:

Be it known that I, ALFRED NOBEL, chemist, a subject of the King of Sweden and Norway, and a resident of 59 Avenue Malakoff, 5 Paris, in the Republic of France, have invented certain new and useful Improvements in Mechanism for Forging Hollow Shafts, Guns, or other Similar Metallic Pieces, of which the following is a specification.

10 Letters Patent have been granted for this invention as follows: in Sweden, dated January 26, 1895, No. 6,627; in Germany, dated June 10, 1895, No. 84,788; in Austria, dated June 11, 1895, No. 45/2,522; in Hungary, 15 dated June 20, 1895, No. 3,057; in Great Britain, dated June 10, 1895, No. 11,346; in France, dated June 10, 1895, No. 248,057; in Belgium, dated July 29, 1895, No. 116,745, and in Italy, Vol. 30, No. 39,463, and Vol. 77, No. 20 252, dated September 30, 1895.

The object of this invention is to subject tubular pieces of steel or other malleable metal intended for guns, hollow shafts, and similar articles to internal pressure for the 25 purpose of molding the same to shape and tempering the metal.

In carrying out this invention the pieces to be operated upon, if not cast or made hollow, are bored through, but in such manner as to 30 make the bore of less diameter than it should have in the final product. A projectile of hard but not brittle steel of a larger diameter than said bore shot from a gun at great velocity is directed so as to pass accurately 35 sighted through the aforesaid bore, which it widens by compressing and expanding the metal. Said projectile should be conical in front and widening so gradually rearward as to avoid too violent traction, and the piece to 40 be treated should of course be solidly fixed. Said operation may be effected either when the aforesaid hollow pieces are heated to redness or to an appropriate heat for softening the metal, or at the ordinary temperature, or 45 at any temperature which the metal operated on is best suited for aforesaid treatment. If said operation is performed at, say, dull redness, the metal is generally so soft as to permit of considerable widening of the bore even

with one single shot; but in order to avoid 50 too violent strain the operation may be repeated with projectiles of gradually-increased diameter. After sufficiently enlarging the bore by the aforesaid treatment while the metal is at, say, a dull-red heat the hollow 55 metal may conveniently be subjected once or more to the same treatment at the ordinary temperature. In the latter case the strain is much greater than at dull redness, and consequently the diameter of the projectile should 60 be little in excess of the diameter of the bore. Since the dimensions of pieces greatly vary, it must be left to practice to establish for each case the best manipulation; but to give an idea of the forces which come into play and 65 the results to be attained it may be mentioned that a gun-bore of fifty-seven millimeters diameter could be enlarged three-fourths of a millimeter by a single shot, the metal being at the ordinary temperature. The metal can 70 be subjected to the aforesaid treatment at red heat, or at the ordinary temperature, or at both temperatures. This operation made at the ordinary temperature serves in a great measure the same purpose as tempering steel and 75 greatly enhances the tensile strength of the metal. Pieces of steel if tempered and annealed so as to preserve sufficient ductility can be rendered still more resisting by being subjected at the ordinary temperature to the 80 aforesaid treatment.

A gun can be rifled by shooting through its smooth bore a rifled projectile of proper diameter, so as to form an extended grooved counterpart of the rifling of the projectile. 85

The aforesaid operation of widening the bore is conveniently made with projectiles shot from smooth-bore guns at great velocity; but it can also be effected by projectiles fired from rifled guns. 90

In the drawings, Figure 1 is a longitudinal section illustrative of the present invention, and Fig. 2 shows the projectile in a larger size.

A is a gun of any suitable construction, and B the tube which is to be operated upon and 95 which is suitably supported.

C and D are hoops which are placed in any convenient manner and connected together

by rods for holding A and B together. At the junction between A and B may be placed a sleeve or muff, so that their ends may be maintained in the adjusted position with respect to the axial lines. During the operation it is evident that each succeeding projectile used for the interior forging of a tube should be of larger diameter than the preceding one, which would necessitate the use of a plurality of guns of different interior diameters; but in order to avoid the use of different guns for the forging of one tube only one gun of an appropriate interior diameter is preferably employed and the projectiles are inserted into a suitable shot-bottom or sabot b, of which all are of corresponding exterior diameter to fit the gun and of different interior diameter to fit the different projectiles to be used.

c is a tightening-disk adapted to take up the pressure of the explosive gases and to prevent leakage of the same.

By this device the same gun may be used to fire a series of projectiles of different diameters. When such a projectile is fired, the fore end of the sabot strikes against the rear end of the tube, the projectile separates from the sabot and passes through the tube to perform its work, and the sabot, with parts belonging thereto, is broken to pieces.

It is evident that the rear end of the tube operated upon need not be in close contact with the fore end of the gun from which the projectile is fired, although it is easier to accurately adjust the tube when close to the gun than when farther away.

I claim as my invention—

1. The combination with a breech-loading cannon and a projectile to be fired therefrom,

of means for rigidly connecting at the front end of said cannon a tube of a size slightly smaller than the projectile, whereby the tube will be forged and smoothed on its interior surface by the rapid passing through it of the projectile, substantially as set forth. 40

2. The combination with a breech-loading cannon and a series of projectiles, of slightly-increasing diameters and sabots to intervene between the cannon and the projectile, of means for rigidly connecting and supporting at the front end of said cannon a tubular article in a highly-heated condition and with the bore slightly smaller than that of the smallest projectile whereby such tubular article will be enlarged and smoothed upon the interior surface by firing through the same the projectiles commencing with the smallest, and the sabots will be broken and pass out in pieces, substantially as set forth. 45 50 55

3. The combination with a breech-loading cannon and a projectile to be fired therefrom, of tie-rods and rings extending from the cannon to a tubular article for supporting the same in front of and in line with the cannon, a sleeve at the junction of the cannon and the rear end of the tube, whereby the tube will be forged and smoothed on its interior surface by the rapid passing through it of the projectile, and the sleeve will confine the gases more or less, substantially as set forth. 60 65 70

In witness whereof I have hereunto signed my name in the presence of two subscribing witnesses.

ALFRED NOBEL.
